UNITED STATES PATENT OFFICE.

JESSE I. RICE, OF NEW YORK, N. Y., ASSIGNOR TO RICE & HOCHSTER, OF NEW YORK, N. Y., A CORPORATION OF NEW YORK.

DESIGN FOR A HAIR ORNAMENT.

48,990.

Specification for Design.

Patented May 2, 1916.

Application filed March 15, 1916. Serial No. 84,496. Term of patent 3½ years.

To all whom it may concern:

Be it known that I, JESSE I. RICE, a citizen of the United States, and resident of New York city, New York, (whose post-office address is No. 87 Fifth avenue, in said city,) have invented a new, original, and ornamental Design for Hair Ornaments, of which the following is a specification, reference being had to the accompanying drawing, forming a part thereof.

Figure 1 shows a front view of the ornament, and Fig. 2 a side view.

I claim:

An ornamental design for a hair ornament as shown.

JESSE I. RICE.
